(57) **CLAIM**

The ornamental design for a latch as shown and described.

DESCRIPTION

FIG. 1 is a perspective view of a knob portion of a handle of a latch according to the first embodiment of the invention;

FIG. 2 is a front view thereof;

FIG. 3 is a rear view thereof;

FIG. 4 is a left side view thereof, the right side view being a mirror image of the left side view;

FIG. 5 is a top view thereof; and

FIG. 6 is a bottom view thereof.

FIG. 7 is a perspective view of a knob portion of a handle of a latch according to the second embodiment of the invention;

FIG. 8 is a front view thereof;

FIG. 9 is a rear view thereof;

FIG. 10 is a left side view thereof, the right side view being a mirror image of the left side view;

FIG. 11 is a top view thereof; and,

FIG. 12 is a bottom view thereof.

Stippling is provided on surfaces of the handle of the latch in selected figures (e.g., FIGS. 1-6) to show surface shading. The stippling does not represent surface texture or color or material, and the latch design is not limited to any particular surface texture or color or material.

The broken line showing is for the purpose of illustrating portions of the latch and forms no part of the claimed design. The broken lines in the handle of the latch correspond to radius lines at changes in radius between adjacent defined surface segments of the handle of the latch.

The boundary (dash-dot-dash) line showing (e.g., in FIGS. 1, 7, and 9-12) delineates the unclaimed region of the latch from the claimed region of the latch.

1 Claim, 12 Drawing Sheets
